UNITED STATES PATENT OFFICE.

HENRY W. O'NEILL, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE SYSTEM.

Application filed May 1, 1923. Serial No. 635,829.

To all whom it may concern:

Be it known that I, HENRY W. O'NEILL, a citizen of the United States of America, residing at Brooklyn, in the county of Kings 5 and State of New York, have invented certain new and useful Improvements in Telephone Systems, of which the following is a full, clear, concise, and exact description.

This invention relates to telephone systems and more particularly to circuits employed in handling toll connections with telephone stations of the so-called coin box pay station types.

Heretofore, in the handling of actual coin transactions in connection with certain kinds of toll or long distance service from stations of the so-called prepayment coin box type, it has been necessary to have the attention of two or more operators. In situations where it may be desired that the charges for a toll connection be collected at a called station rather than at a station at which the call may have originated, it has usually been necessary for a toll operator 20 at the originating point to call and repeat the particulars of the call to a toll operator at the inward or terminating point, the latter operator then proceeds to handle the call in substantially the same manner in which 25 a call originating at the called station would have been handled. This renders it possible for the toll operator to obtain the assistance of a trunk or toll switching operator, also the assistance of a tandem operator 30 on built uptrunk connections, relative to the disposal of coins, such as their return to a patron on incompletely calls, or the collection of the coins within the coin box on calls which may be successfully completed.

It is, therefore, broadly, an object of this invention to provide a system wherein a single toll operator may have complete control of collect and refund operations in such a 45 manner as to improve and expedite service in connection with coin box stations.

This object is attained in accordance with the preferred form of this invention by the provision of a plurality of selectively responsive relays at the inward end of a toll switching trunk arranged to be controlled by a toll operator to selectively effect response of coin collect and refund mechanism at a distant sub-station.

A feature of the invention resides in the control of collect and refund operations by a toll operator on a connection built up over one or more toll lines and finally over a toll switching trunk to a called coin box station at which it may be desired that the charges for a call be collected rather than collection being made at the station of the calling party.

A further feature provides for the return of distinctive signals to a toll operator to respectively indicate that collect or refund operations have properly taken place at a coin box station.

A still further feature resides in the display of signals at a local office simultaneously with the transmission of signals to a toll operator to indicate to the local operator, the proper functioning of the coin box mechanism.

Another feature provides for dual equipment on toll switching trunks whereby either a toll switching operator or a toll operator may control coin collect or refund operations.

Still another feature provides means whereby a toll operator may signal and speak to a toll switching operator for the purpose of instructing the toll switching operator to carry out a collect or refund operation, etc.

A disclosure of the subject matter of this invention has also been made in a copending application which is a division of the present application. This copending application of H. W. O'Neill, Serial No. 741,320, filed October 3, 1924, relates to a supervisory signaling arrangement for improving and expediting the service in establishing, maintaining, and disestablishing of toll connections in the so-called coin box pay station type of systems covered by the present application.

The above and other features of the invention may be readily understood from the following detailed description taken with the accompanying drawings.

Referring to the accompanying drawings, Fig. 1 shows equipment at C for the inward end of a trunk circuit L¹ and equipment at a coin box subscriber's station A, while in Fig. 2 a toll operator's cord circuit is shown at E and an inward or through toll operator's cord circuit is shown at D.

It will be assumed that a connection from the outward toll operator's position at E is to be built up over a toll line L^2 by way of the cord circuit at the inward toll position 5 D, and the trunk circuit L^1 to the line circuit of the station A.

Assuming further that on the present call the charges are to be reversed or collected at the called station A, the originating operator at E inserts plug 201 into jack 202 of the toll line L^2 and by operating a signaling key 230, a signal (not shown) will be displayed at the distant point D. In response to this signal, the operator at 10 D inserts plug 101 into jack 102 of the line L^2 and by the operation of a talking key, (not shown) may communicate with the operator at E and receive request for a connection with the subscriber at station 15 A. The inward operator at D then employs an order wire, (not shown) to relay the request to a toll switching operator at C who has access to the line A. The toll switching operator may assign the trunk 20 25 L^1 for use in establishing the connection and thereupon insert plug 3 into jack 4 of the called line, while the operator at D inserts plug 105 into jack 106 of the assigned toll switching trunk.

30 The insertion of plug 105 into jack 106, establishes a circuit for a relay 50 which may be traced from ground battery, resistance element and left hand winding of relay 50, normal right hand make-before-break contacts of relay 75, upper right hand winding of repeating coil 85, tip contacts of jack 106 and plug 105, upper left hand winding of repeating coil 110, windings of relay 120, lower left hand winding of repeating coil 110, ring contacts of plug 105 and jack 106, lower right hand winding of repeating coil 85, normal left hand make-before-break contacts of relay 75 and thence to ground through a resistance element and the right hand winding of relay 50.

Relay 50 in its operated position applies grounded battery through its right hand contact, to conductor 9 from which three branch paths extend, the first may be traced 50 through the winding of a relay 25 and the normally closed contacts of the circuit controlling element associated with relay 10 to ground; the second path extends through the winding of a relay 20 and thence to ground through the normal contacts of the circuit controlling element of relay 5, while the third path extends through the winding of a relay 15 and thence to ground through the normal contacts of the circuit controlling element associated with relay 1. The relays 15, 20 and 25 respond and continue actuated since the contacts of the relays 1, 5 and 10 are normally closed and may separate only during periods when alternating currents of proper respective frequencies

may be applied to their windings, as presently will appear.

Assuming that the call signal at the station A has been operated in a manner presently to be described, and response received, the acceptance of the collect call by the subscriber is obtained by the operator at E, who further requires the deposit of the necessary amount in coins in the coin box.

As each coin is inserted in the slot of the coin box a characteristic tone is manifested to the operator at E who may thereby verify deposit of the proper amount by the subscriber. Such tone signals are well understood by those skilled in the art and any further description here will not be necessary. The operator at E may now proceed to collect the coins by the actuation of collect key 205 of the cord circuit at her position, thereby applying alternating currents of 700 and 1500 cycles per second from the sources 207 and 208 respectively, through the windings of the acceleration type alternating current relays 1 and 10. This circuit may be traced from the sources 207 and 208, alternate upper and lower contacts of key 205, upper and lower normal contacts of key 230, tip and ring contacts of plug 201 and jack 202, line conductors of the line L^2 , tip and ring contacts of jack 102 and plug 101, right hand winding of repeating coil 110 from whence currents of like frequencies are induced in the left hand winding of this repeating coil and flow out over the tip and ring contacts of plug 105 and jack 106, line conductors of line L^1 and thence through the windings of relays 1, 5 and 10 which are bridged across the line conductors of the line L^1 . Relays 1, 5 and 10 are respectively responsive to currents of 700, 1100 and 1500 cycle frequencies so that in the circuit just traced, relays 1 and 10 alone operate, while relay 5 continues in its normal condition. Relays 1 and 10 in operating, effect the release of relays 15 and 25 respectively whereupon a circuit may be traced from ground battery, right hand armature and front contact of relay 50, conductor 9, winding of a relay 18, armature and back contact of relay 15, middle armature and front contact of relay 20, middle armature and back contact of relay 25, conductor 19 thence to ground through the winding of a relay 30. Relay 30 operates and opens the tip and ring conductors of the trunk circuit L^1 , and connects relatively high potential direct current of positive polarity from a source 54 by way of the right hand armature and back contact of relay 55, winding of relay 60, front contact and upper armature of relay 3, tip contacts of plug 30 and jack 4 thence to ground through the windings of magnet 6 and coin contacts 7 in the coin box at the station A.

The magnet 6 operates in this circuit and causes the coins to be deposited in the collect chamber of the coin box.

Relay 60 operates in the circuit just traced and connects the 400 cycle current source 63 across the talking conductors of the terminating equipment of line L^1 , from whence this current may pass through the repeating coil 85', tip and ring contacts of jack 100 and plug 105, repeating coil 110, tip and ring contacts of plug 101 and jack 102, line conductors of line L^2 , tip and ring contacts of jack 202 and plug 201, normal upper and lower contacts of key 230, 400 cycle filter 210, normal upper and lower contacts of key 220 and thence by way of a listening key 215, and leads indicated OT extending to the operator's telephone set, not shown. This 400 cycle current produces a tone signal in the operator's telephone set indicating to her that the proper functioning of the coin box mechanism has taken place and that the coins have been deposited in the proper receptacle. The object of the signal 81 for which an obvious circuit is established by the actuation of relay 60 will hereinafter be pointed out.

Should the operator at E desire to refund rather than collect the coins deposited at the station A, the key 220 on the cord circuit at E may be operated, thereby applying currents of 1100 and 1500 cycles per second from the sources 217 and 218 respectively, to the windings of the distant relays 5 and 10. This circuit may be traced from sources 217 and 218, alternate upper and lower contacts of key 220, upper and lower normal contacts of keys 205 and 230, thence over the main conductors of the connection as already traced, to complete the circuit through the windings of relays 1, 5 and 10. Relays 5 and 10 are respectively responsive to currents of 1100 and 1500 cycle frequencies and operate in the circuit just traced to effect the release of relays 20 and 25 respectively. A circuit may now be traced from grounded battery, front contact and right hand armature of relay 50, conductor 9, winding of relay 18, armature and front contact of relay 15, outermost left hand armatures and back contacts of relays 20 and 25, conductor 29 to ground through the winding of a relay 35. Relay 35 now operates and opens the talking conductors of the connection and establishes a circuit from a negatively poled and grounded battery 56, left hand armature and back contact of relay 55, winding of relay 65, front contact and upper armature of relay 35, back contact and upper armature of relay 30, tip members of plug 3 and jack 4 and the windings of magnet 6 to ground through coin contacts 7. Under the negative polarity of battery 56 magnet 6 attracts its armature in a direction opposite to that described heretofore in

connection with the application of positive current from the source 54 and the coins are thereupon deflected into the refund receptacle of the coin box at the station A.

Relay 65 operates in the circuit just traced and effects the transmission of 2000 cycle frequency current from source 67 over the path already traced in connection with the transmission of the 400 cycle current from the source 63 except that a 2000 cycle filter 225 will be rendered effective in this circuit due to the actuated position of the key 220, while the 400 cycle filter 210 will stand disabled due to the key 205 being in its normal position. The 2000 cycle current sets up a distinctive tone signal in the operator's telephone set at E to indicate that the coins have been properly disposed of at the coin box at station A. Lamp 82 is actuated due to the operation of relay 65, the object of this will be described hereinafter.

It will be apparent from the foregoing that a cord circuit similar to the cord at E may be joined directly to the trunk L^1 as in connecting a calling subscriber's station directly from an outward operator's position, and that the same procedure and operations may effect the collecting or refunding of coins at the station A while the reception of signals by the toll operator may be had in a manner similar to that just described.

The present system provides for the control of the ringing of a subscriber's station by a toll operator irrespective of whether a connection may include a toll line, an inward cord circuit and a toll switching trunk or whether the connection may be formed directly from a toll position by way of a toll switching trunk only.

In carrying out a ringing operation under the present assumed connection by way of the toll line L^2 , the operator at E may actuate the ringing key 230 thereby applying currents of 700 and 1100 cycles from sources 233 and 234, respectively, to the main conductors of the connection. These currents may traverse a path extending from the sources 233 and 234, normal contacts of keys 275 and 280, upper and lower alternate contacts of key 230, tip and ring contacts of plug 201 and jack 202, line conductors of line L^2 , tip and ring contacts of jack 102, and plug 101, through the repeating coil 110, tip and ring contacts of plug 105 and jack 106 and thence through the windings of relays 1, 5 and 10. Relays 1 and 5 respond to the incoming frequencies and effect the release of relays 15 and 20 whereupon a circuit may be traced from grounded battery, front contact and right hand armature of relay 50, conductor 9, winding of relay 18, armature and back contact of relay 15, innermost armature and back contact of relay 20, innermost armature and front contact of relay 25, conductor 39, to ground through

the winding of relay 40. Relay 40 operates and disconnects the main conductors of the connection in establishing a circuit which may be traced from a source of grounded 5 ringing current 31, front contact and lower armature of relay 40, lower armatures and back contacts of relays 30 and 35, ring members of plug 3 and jack 4, signaling apparatus at station A, tip members of jack 4 and 10 plug 3, upper armatures and front contacts of relays 30 and 35, upper armatures and front contacts of relays 45 and 40 (operated as already described) to ground.

Having described the manner in which a 15 toll operator at E may control the coin collect and refund mechanism at the substation A and also the manner in which the subscriber at substation may be signaled by the toll operator at E, attention will now be 20 directed to the manner in which supervision is obtained in the present system.

The insertion of plug 201 into jack 202 as hereinbefore described, established a circuit which may be traced from grounded 25 battery through the circuit controlling elements associated with relays 250 and 255, the contacts of key 253, armature and upper contact of relay 260, the lower winding of relay 260, conductor 262, and thence to 30 ground over the sleeve members of plug 201 and jack 202. It will be noted that under this circuit condition, relay 265 is shunted by the battery current just traced through the circuit controlling elements of relays 35 250 and 255 and the relay 265 therefore continues inert at this time. A relay 270 may operate however in a circuit extending from 40 grounded battery, armature and back contact of relay 265, winding of relay 270, upper winding of relay 260, conductor 262, to ground over the sleeve members of plug 201 and jack 202.

The insertion of plug 101 into jack 102 at 45 D and the actuation of a talking key (not shown) but which may be assumed as also controlling side contacts 115 thereby effects completion of a circuit which may be traced from grounded battery, circuit controlling elements associated with relays 135 and 145, 50 winding of relay 150, key contacts 115, sleeve members of plug 101 and jack 102 to ground. Relay 150 operates and locks up in the same circuit as effected its initial energization except that the right hand armature and front 55 contact of this relay are substituted for the key contacts 115. The energization of relay 150 prevents the illumination of lamp 109 at this time.

60 Insertion of plug 105 into jack 106 completes an energizing circuit for relay 50 as heretofore described and assuming that plug 105 has been inserted in the jack 106 at D, in advance of the insertion of plug 3 into jack 4 at C, the resulting operated condition 65 of the relay 50 and the inert condition of the

relay 45, permit grounded battery to flow through a lamp signal 7, lower armature and back contact of relay 45, left hand winding of relay 75 to ground through the front contact and left hand armature of relay 50. 70 The illumination of lamp 7 in this instance serves as a guard signal to inform the operator at C that the trunk L¹ has been taken for use at its outer end.

Relay 75 operates in the circuit just traced 75 and in operating, reverses the polarity of the battery current supplied through the windings of relay 50 with respect to the main conductors of the line L¹. This polarity will now be such that the polar relay 120 will 80 continue in the position shown in the drawing, to maintain the lamp 107 disconnected. This serves as a negative form of guard signal to the operator at D indicating that the connection has not been completed at the 85 point C, in other words, that the line of the called subscriber has not yet been connected. When the called subscriber's line is taken by the insertion of plug 3 into jack 4, the circuit for relay 75 is opened at the lower contacts of relay 45 and relay 75 releases to restore the original polarity in the loop formed of line L¹ thereby effecting operation of relay 120 to energize the lamp 107 over an 90 obvious circuit.

At the instant relay 120 responded, the application of grounded battery associated with the armature of relay 120 effects the charging of a condenser 121 in series with the winding of relay 125. Momentary response of the relay 125 due to the charging of the condenser disconnects alternating current relays 135 and 145 and applies alternating currents at 900 and 1700 cycles per second from sources 130 and 134, respectively, to the main conductors of the cord circuit at D whereupon correspondingly tuned relays 250 and 255 are actuated over a circuit extending from the sources 133 and 134, alternate contacts and armatures of relay 125, tip and ring members of plug 101 and jack 102, line conductors of line L², tip and ring contacts of jack 202 and plug 201, upper and lower normal contacts of keys 230, 205 and 220 thence through windings of relays 250 and 255. These relays are actuated and momentarily disconnect battery from the lower winding of relay 260 so that the current present through the upper winding of relay 260 causes the armature of this relay to contact with the lower alternate contact. On cessation of the impulse of alternating currents the relays 250 and 255 restore and battery is again connected to the armature of relay 260 now contacting with its lower contact so that relay 270 will be shunted thereby releasing its armature to complete a circuit for relay 265 extending from grounded battery, armature and back contact of relay 270, winding of relay 265, lower winding 115

105

110

115

120

125

130

of relay 260, conductor 262 to ground over sleeve contacts of plug 201 and jack 202. Relay 265, in operating, establishes an obvious circuit for lamp 227. The illumination of lamp 227 indicates to the operator at E that the connection has been extended to the line of the called party and she may proceed to ring the called party by operating key 230, the effect of which has heretofore been described.

When the subscriber at A responds to the signal and removes the receiver from the switchhook, a circuit for relay 80 is established from grounded battery, winding of relay 80, resistance element and lower left hand winding of repeating coil 85, back contact and lower armature of relay 40, lower armatures and back contacts of relays 30 and 35, ring members of plug 3 and jack 4, line loop and apparatus at station A, tip members of jack 4 and plug 3, upper armatures and back contacts of relays 30 and 35, upper armature and front contact of relay 45, upper armature and back contact of relay 40 to ground through the upper left hand winding of repeating coil 85 and the resistance element associated therewith. The operation of relay 80' causes the actuation of relay 75 in a circuit extending from grounded battery, right hand winding of relay 75, front contact and armature of relay 80', left hand winding of relay 75, to ground over the front contact and left hand armature of relay 50. The actuation of relay 75 reverses the current polarity in the loop of the trunk L^1 causing the release of relay 120 to deenergize the lamp 107. At the instant the contacts of relay 120 separated, the discharge of the condenser 121 through lamp 107 and relay 125 causes a momentary response of relay 125 to effect a corresponding application of the 900 and 1700 cycle currents from the sources 133 and 134 to cause a momentary response of relays 250 and 255 at E in a manner hereinbefore described. The resulting disconnection of current from the armature and upper winding of relay 260 permits the current now flowing in the lower winding of this relay to move the armature to its upper contact whereupon current from the battery associated with the circuit controlling elements of relays 250 and 255 on restoration of these relays, will shunt and effect release of the relay 265, whereupon the energizing circuit for lamp 227 is interrupted and battery will be reconnected through the winding of relay 270 by way of the upper winding of the relay 260.

In the present assumed talking condition of the connection, the signal lamps 7, 107, 109 and 227 at their respective points are extinguished. The signal lamp 237 will also be extinguished due to the polarity of current in a toll switching trunk, not shown,

but which would ordinarily be present at the right hand side and joined to that end (not shown) of the cord circuit at E. A polar relay 285 serves to control the lamp 237 on such a connection.

Should the party at station A flash the switchhook thereat, corresponding responses of relays 80' and 75 at C, 120 and 125 at D, 250, 255, 260, 265 and 270 at E will cause the lamps 107 and 227 to be flashed at the points D and E respectively. The condition of these lamps with respect to the last movement of the switchhook in the flashing operation will depend on whether the subscriber at A abandons the connection by placing the receiver on its switchhook or whether in wishing to reach an operator, the party may retain the receiver off its switchhook. In the former case, the lamps will continue lighted while in the latter the lamps will stand extinguished.

From the foregoing it will be obvious that disconnection at the station A will result in the illumination of lamps 107 and 227. This will serve as a disconnect signal at the point E but not necessarily so at the point D where under traffic procedure for any situation where it may be desired, an operator at such a point may disconnect only on receipt of a signal from the operator at E as may be displayed on the lamp 109. The operator at D may adhere to the indications of signal lamp 109 at all times except in cases where flashing of the signal 107 or the steady display of this signal may continue beyond a reasonable length of time, and render it advisable for this operator to cut in on the connection and disconnect or take such steps as appear necessary in case the call for any reason is not being properly supervised by the operator at E. This in effect, constitutes a check by means of a tandem arrangement relative to a plurality of operators on one and the same connection and insures more immediate release of important toll line circuits so that they may not be unnecessarily held.

In case the operator at E may desire the attention of the operator at D on a connection, the actuation of a master key 275 followed by successive operations of the ringing key 230 in a manner to correspond with flashing effects or intermittent applications of alternating currents of 1500 and 1300 cycles from the sources 235 and 236 to the line L^2 to effect corresponding responses of the alternating current relays 135 and 145 at D. As already described, the relay 150 may be assumed to be in its operated position. Therefore the first response of relays 135 and 145 will disconnect battery to permit the restoration of relay 150 to separate its lower or locking contacts while the lamp 109 may be illuminated over an obvious circuit from the grounded sleeve strand of the cord

through the left hand normal contacts of relay 150 and the contacts of relays 135 and 145 to grounded battery. Following the first response of relays 135 and 145, each subsequent energization thereof due to flashing of the distant key 230 disconnects the battery to extinguish the lamp 109. Obviously, the lamp 109 will flash in phase with movements of the key 230. In actuating the talking key (not shown) at D in response to this signal, the contacts 115 will be closed to initially energize relay 150 which immediately locks and extinguishes the lamp 109 as hereinbefore described.

15 It may be noted that the 1500 cycle current of the 1300 and 1500 cycle impulses just described in connection with the operations of relays 135 and 145 at D may also effect an idle operation of relay 10 at C. The operation of this relay will be without effect, however, as during the released period of relay 25, the lead 19 will stand disconnected at the normal contact of relay 15, lead 29 will stand open at the left hand normal contact of relay 20 while lead 39 will be open at the right hand forward contact of relay 25 and also at the normal contacts of relays 15 and 20 while the lead to relay 95 will stand open at the normal contacts 30 of relays 15 and 20.

In situations where it may be desired that an operator at D may regularly disconnect on display of the signal 109 only, an operator at E may proceed as already described for the flashing operation except that a single operation only of the ringing key 230 will be required. This will effect release of relay 150 to light the signal lamp 109, the steady display of which will indicate that the cord 40 at that point may be taken down irrespective of the conditions of the signal 107 thus insuring immediate release of the equipment involved.

In controlling the display of the disconnect signal at the point C, removal of the plug 105 from jack 106 at D effects the release of relay 50, the left hand normal contacts of which apply ground potential by way of a resistance unit 88, lowermost forward contacts of relay 45 and the lamp 7 to grounded battery. At this time, the release of relays 15, 20 and 25 also results from the separation of the right hand contacts of relay 50. In response to the display of signal 7, the operator at C removes plug 3 from jack 4 whereupon the apparatus at this point restores to normal.

From the foregoing description, it will be clear that for connections where the cord circuit at E may be employed directly with a circuit such as trunk L¹, as would be done in reaching a local or home subscriber, the relay 285 and associated lamp 237 may serve in the same manner as the relay 120

and lamp 107 to display a guard, ringing, 65 and a flashing or disconnect signal.

At the point C, keys 91, 92 and 93 may be controlled by a toll switching operator at this point for respectively collecting or refunding coins at a connected pay station and for ringing on a line to which plug 3 may be connected. In situations where positions or offices not provided with equipment similar to that shown at E, may have access to trunk circuits of the present type terminating at the point C, requests by way of an order wire circuit may be made relative to the operator at the latter point carrying out coin control operations while the toll operator may listen on the connection for the verifying tone signals.

The present system further provides that when a collect call may encounter a pay station of the coin box type, the toll switching operator may depress a talking key 48 and directly advise a distant calling operator that the call is for such a station. It is also provided that a calling operator may operate a signal associated with a trunk circuit whereupon the toll switching operator may come in on the circuit by means of the key 48.

Assuming that a connection is established from the point E to the point C, the operator at E may actuate a second master key 280 and then operate the ringing key 230. A resulting application of alternate currents at 700, 1100 and 1500 cycles from sources 233, 234 and 235 will effect the joint response of relays 1, 5 and 10 to release the associated relays 15, 20 and 25 at C. Battery may then extend from conductor 9, winding of relay 18, normal contacts of relay 15, the innermost normal contacts of relays 20 and 25, thence through the normal contacts and winding of relay 95 to ground through normal contact on the talking key 48.

On response of relay 95, its forward contacts form a self-locking circuit and effects the illumination of call lamp 47 in series with the winding of this relay. Depression of the key 48 when the toll switching operator responds to such a signal, disconnects the ground to release the relay 95 and thereby extinguish the lamp 47. Such calls as have been referred to are mainly indicated to expedite the service relative to providing that a controlling toll operator may communicate directly with a toll switching operator relative to matters concerning the particular connection, or the trunk

operator may speak directly with a station which may be joined by way of plug 3. Such communications may, in general, refer to verification of a line relative to number, class of service, denied toll service, etc., or to any apparent irregularities in the operation or control of a coin box equipment

- as will be referred to more in detail later on. In connection with or aside from coin box pay station service, an originating toll operator on a so-called person-to-person call where 5 the called party may not be at the station signaled may, on information obtained from such station, "signal-in" and request the toll switching operator to change the connection of the trunk circuit to the line of another 10 station at which the information obtained may indicate that the person wanted may be found. In situations where it may be desired, the associated order wire may be dispensed with, a toll operator on either 15 a direct or a built-up connection may call and talk to the toll switching operator over the trunk circuit in requesting that the trunk circuit be connected to the line of a station under call. 20 The lamp signals 81 and 82 associated with collect and refund operations as already described, serve for indicating the presence of and the proper deposit of coins at a connected station in situations where the 25 toll switching operator may manipulate the keys 91 or 92 in response to a request received over an order wire circuit or over the trunk circuit proper, by means of the signal 47 and the key 48. The lamps 81 and 30 82 also permit a toll switching operator to note any irregularities with respect to the coin control equipment when a distant operator may be directly handling a collect or a refund transaction. 35 As an aid to high grade transmission on toll connections, the talking battery current supplied to the transmitter of a connected station is of higher potential than the current supplied for the same transmitter on a local connection. Therefore, provision is 40 made against the possibility of the slot or coin magnet 6 retaining its armature through insufficient time having intervened between the instant the coin control current may have 45 been disconnected and the talking battery reestablished due to rapid switching as may be effected by the restoration of relay 30 or relay 35 under respective collect or refund operations. This contingency is guarded 50 against by the employment of relays 55, 80 and 85 and an interrupter 86, the operation of which will now be described. 55 Assuming that the relay 30 corresponding with "collect" is now in its operated position, coin collect current will be routed through the winding of relay 60 as already described. The latter relay in addition to applying current at 400 cycles per second back over the line, also applies ground potential through the lamp signal 81, the forward contacts of relay 18, left hand normal contact of relay 85 and thence to grounded battery through the left hand winding of relay 80. In addition to lighting the lamp 81 as a collect pilot 60 signal, current in this circuit causes relay 65 to respond following which the forward contacts of this relay prepare a circuit from grounded battery through the right hand windings of relays 80 and 85 to the interrupter 86. The instant ground potential 70 is applied through the interrupter 86, current through the circuit traced effects response of relay 85 which interrupts the circuit through the left hand winding of relay 80 and substitutes current from grounded battery through the left hand winding of relay 85 and its left hand forward contacts for the purpose of retaining this relay and also for continuing the energization of lamp 81. Upon disconnection of ground at the 80 interrupter 86, relay 80 is released to prepare a circuit extending from grounded battery through the winding of relay 55, right hand contact of relay 85, normal contacts of relay 80 and thence through the right hand winding of relay 85 to the interrupter 86. On the next application of ground potential through the interrupter, the response of relay 55 disconnects the source of coin battery 85 90 95 100 105 110 115 120 125 130 54 from the line circuit. The resulting release of relay 60 disconnects ground to extinguish lamp 81 and also to interrupt the holding circuit through the left hand winding of relay 85. Therefore, on the disconnection of ground at the interrupter 86, relays 85 and 55 will release thereby returning the circuits to normal condition as shown in the drawing. Disconnection of coin battery 54 by response of the relay 55 permitted the release of the armature of the slot magnet 6 at station A, thereby disconnecting ground at that point. Therefore, when relay 55 restores as described, the circuit including battery 54 will be opened so that relay 60 will not reoperate. 115 In the event that trouble may be present at the coin box, whereby coins may be wedged or clogged or if for any other reason, the associated ground may continue, the cycle of operations relative to the response of relays 80, 85 and 55 as just described, will be repeated during such period as the relay 30 may continue energized through the associated key 91 or through response of relays 1, 5 and 10 to alternating currents supplied from a distant toll operator's position, as described. Under refund operation, the relay 65 applies ground to light the lamp 82 and to effect the operation of relays 80 and 85 in order to produce a cycle of operations similar to those just described for a coin collect operation. During such cycles, the lamp 81 or the lamp 82 will be flashed while correspondingly spaced impulses of alternating current at 400 or 2000 cycles per second from the respective sources 63 or 67 due to response of relays 60 or 65 will be sent back and manifested in the receiver of the distant controlling toll operator. In this manner, irregularity at the coin box will be made

known to the toll switching operator at the same instant that it may be indicated to the distant toll operator, and ordinarily, would represent an instance where it would be advisable for the toll operator to communicate with the toll switching operator as may be accomplished by means of the key 48 and the lamp 47 as already described.

The purpose of the ground connection 10 from the lowermost forward contacts of relays 30 and 35 by way of the resistance 94 is to provide for retaining supervisory relay 80 and thereby the relay 75, during periods in which coin operation control may be under 15 way through either one of the relays 30 or 35. This insures that a premature disconnect signal will not be returned and manifested on the signal 107 at D and on the signal 227 at E.

20 In regard to the employment of a plurality of alternating currents and a corresponding number of respectively tuned relays for the translation of signals, the requirement relative to joint response of two or more 25 relays before a translation may be affected, is mainly to insure that voice currents may not become effective during the period of conversation to establish a premature or false signaling effect. The various frequencies indicated have been chosen mainly for convenience in illustrating and describing 30 the system.

The key 253 at E provides that the operator may predeterminedly affect the signal 227 35 during the period of connection, that is, assuming the lamp 227 to be lighted, momentary depression of the non-locking key 253 may cause the lamp to be extinguished by thus removing battery from the 40 armature and upper winding of relay 260, while conversely, assuming the lamp to be extinguished, momentary depression of the key 253 removes battery from the armature and lower winding of relay 260 whereupon 45 the lamp 227 will be lighted. Ordinarily, the manual setting of the signal 227 will not be required and the key 253 is provided only for rare or unusual situations where irregularity may result in the signal being positioned out of sequence or phase relation to 50 the signaling effects described.

What is claimed is:

1. In a telephone system, a toll line opaque to direct current, sources of alternating current associated with one end of said line, a coin box associated with the other end of said line, and means also at said other end of said line responsive to alternating currents from said sources for operating 55 said coin box.

2. In a telephone system, a toll line opaque to direct current and having maximum transmission efficiency within a particular band of frequencies, sources of alternating current of frequencies within said 65

band associated with one end of said line, a coin box associated with the other end of said line, and means also at said other end of the line responsive to alternating currents from said sources for operating said coin 70 box.

3. In a telephone system, a toll line, sources of alternating current associated with one end of said line, a coin box mechanism associated with the other end of said line, means including a plurality of relays also at the other end of said line responsive to various combinations of said alternating currents for selectively actuating said relay in various combinations to effect the operation 80 of said coin box mechanism in various ways, and means for transmitting signals characteristic of the different operations of said coin box mechanism to the opposite end of said line.

4. In a telephone system, a substation, a coin box mechanism thereat, an operator's position, a link circuit employed in establishing a connection between said substation and said position, a bridge associated with 90 said link circuit including a plurality of selectively responsive relays, and means under the control of said relays to effect the actuation of said mechanism in a manner corresponding to a certain setting of said 95 relays, the setting thereof being controlled from said position.

5. In a telephone system, a subscriber's station, a coin box mechanism thereat, an operator's position, a link circuit employed 100 in establishing a connection between said station and said position, a plurality of relays in bridge of said link circuit, and means at said position for actuating said relays in various combinations to effect the operation 105 of said mechanism in various ways.

6. In a telephone system, a subscriber's station, a coin box mechanism thereat adapted to register refund and collect operations, an operator's position, a link circuit employed in establishing a connection between said station and said position, a group of relays associated with said link circuit, a plurality of current sources of different characteristics, and means at said position 110 for applying certain of said sources to said link for actuating said group of relays in a certain manner to effect the refund operation of said mechanism and for applying certain other of said sources to said link for 115 actuating said group of relays in another manner to effect the collect operation of said mechanism.

7. In a telephone system, a subscriber's station, a coin box mechanism thereat, inward and outward toll operators' positions, means including a toll switching trunk, a toll operator's cord and a toll line circuit for interconnecting said positions and said 125 station, and means associated with said 130

trunk circuit and controlled from each of said positions for operating said coin box mechanism.

8. In a telephone system, a station, a receptacle for coins thereat, a toll position, a plurality of switching points intermediate said station and said position, line circuits for joining said station and said position by way of said switching points, a plurality

of sources of alternating current, means for 10 selectively applying said sources to said line circuits, and means controlled by the applied currents for disposing of coins which may be present in said receptacle.

In witness whereof, I hereunto subscribe 15 my name this 27 day of April A. D. 1923.

HENRY W. O'NEILL.
